VALUE PRINTING MACHINE

Johan Georg Christian Möller, Oslo, Norway,
assignor to Krag Maskin Fabrik A/S., Oslo,
Norway

Application July 6, 1932, Serial No. 621,097

4 Claims. (Cl. 101—91)

This invention relates to improvements in postal value printing machines of the type where the digit wheels are provided with adjustable printing types and in which simultaneously with the setting of the digit wheels, a corresponding number of teeth are caused to assume operative position for cooperation with a suitable counting device. The invention has for its object to improve the digit wheels and the radially movable types and the combination of these wheels with the mechanism for securing the necessary displacement of these types.

In the accompanying drawings wherein an improved embodiment of the invention is illustrated:

Figure 1 is a diagrammatic view of the complete machine partly broken away and showing the invention applied thereto.

Fig. 2 is an enlarged sectional view of the mechanism constituting the invention.

Fig. 3 is a section on the line 3—3 of Fig. 2.

Fig. 4 is a section on the line 4—4 of Fig. 2.

Fig. 5 is a view similar to Fig. 4 showing a modification of the invention.

Fig. 6 is a fragmentary vertical sectional view through the machine illustrating the mechanism for setting the digit wheels.

Referring to the drawings in detail and in particular to Fig. 1 the complete postal value printing machine is shown diagrammatically. A shaft 4 is rotatably mounted in the machine frame and supports a set of digit wheels designated generally at C and a set of counter actuating wheels A each

of which consists of a cam disk 6. As shown in Fig. 2 the ends of the tubular shafts 5 are arranged in stepped relation and the cam disks 6 are secured thereto by means of keys 7 engaging in slots 8 in the tube. Each cam disk 6

operates with a gear 10 having a plurality of radially movable teeth 11 guided in radial grooves 11' provided in the gear wheel 10. The teeth 11 are provided with laterally projecting pins 12 arranged in the cam slots 13 in the disks 6 whereby when said disks are turned relative to the gear wheels 10, the teeth 11 are successively moved outwardly to operative position in number depending on the extent of relative angular movement of the disk 6 and the gear wheel 10.

The ends of the tubular shafts 5 opposite the

counter actuating wheel set A are also arranged in stepped relation and are non-rotatably secured in digit wheels 14 carrying radially displaceable bars 15 having type on the outer terminals thereof of values ranging from zero to 9. The type bars 15 are provided with laterally projecting pins 16 engaged in cam slots 17 in the disks 18.

At one side of the set of wheels 14, a disk 19 is arranged and which is secured to and rotatable with the shaft 4. At the opposite side of the digit wheels is arranged a second disk 20 which is rotatably mounted on the outermost tubular shaft 5 and the two disks 19 and 20 are coupled in spaced relation by the bar 21 having an opening therein as shown in Fig. 4 through which the type bars 15 may be projected to operative position. In this manner the disks 19 and 20 together with the bar 21 are secured to and rotate as a unit with the shaft 4.

A spacing sleeve 23 is mounted on the outermost tubular shaft 5 interposed between the disk 20, and the nearest adjacent wheel 10 and nuts 25 are fitted on a threaded portion of the shaft 4 and are adjusted so as to maintain the parts 25 constituting the assemblages A and C in proper relative position by means of a pressure disk 24 with which said nuts coat.

The cam disks 18 are provided with projections 22 which embrace the bar 21 and are thus held against rotary movement relative to the shaft 4. The prominent point of each cam slot 17 is arranged adjacent the opening in the bar 21 and thus as the wheels 14 are rotated relatively to the shaft 4 and the cam disks 18 the type bars 15 carried thereby are successively moved outwardly by the pins 16 to the operative position shown in Fig. 4 and are thus disposed in position for printing.

The gear wheels 10 and the disk 24 are provided with peripheral grooves 26 engaged by a bar 27 secured to the disk 20 whereby said wheels 10 and the disk 24 are held against rotary movement relative to the shaft 4 and the disks 19 and 20 and digit wheels 14.

The mechanism for setting the digit wheels 14 is illustrated in detail in Fig. 6 and is partly shown in Fig. 1. This mechanism consists of a member 94 forming part of the machine casing and having slots 93 therein corresponding in number to the number of digit wheels. The walls of each slot 93 are formed with arcuate grooves 95 receiving a slide member 96 through which extends a setting rod 97. The slide members 96 are provided with upright arms 98 passing

through the slots 93 and provided with guides 99 for the setting rods 97. The guides 99 each abut a sleeve 100 which, together with an upper sleeve 101 to which the rod 97 is secured by means of a nut 102, enclose a spring 103 normally holding the rod 97 in raised position. The rods 97 have angular portions 104 which in the raised positions of the rod abut against a guide member 105. When a rod 97 is depressed, the lower end thereof enters a recess 106 in the corresponding digit wheel whereby the latter may be rotated to the desired extent by moving the setting rod 97 and slide member 96 arcuately through the slot 93.

From the foregoing it will be understood that each of the digit wheels 14 corresponds with one of the actuating wheels 10 and as one of the wheels 14 is turned by its setting rod 97 to a position corresponding with the value to be printed, the type bar 15 is moved to operative position as shown in Fig. 4. Simultaneously with this adjustment the corresponding tubular shaft 5 is turned through the same angle and the movement thereof is transferred to the related cam disk 6. In this manner a number of displaceable counter actuating teeth 11 is projected outwardly to operative position as shown in Fig. 3 corresponding with the value represented by the projected type bar 15. In this manner a value is set up in the wheels 10 depending on the number of teeth 11 projected outwardly which corresponds with the value set up in the printing bars 15.

During the rotary movement of the shaft 4 following the above mentioned adjustment, the printing of the desired value is effected and the value set up in the wheels 10 is transferred to a suitable counting device (not shown).

In the modification of the invention illustrated in Fig. 5 both the type bars 15 and the teeth 11 are arranged on one digit wheel 14a and the cam disk 18a is provided with the cam slots 13a and 17a coacting respectively with the pins 12a and 16a of the adjustable counter actuating teeth 11a

and the type bars 15a. According to this arrangement, as the digit wheel 14 is turned relatively to the cam disk 18a, a number of counter actuating teeth 11a is projected corresponding with the value of the type bar 15a which is moved to operative position. 5

What I claim is:

1. In a machine of the character described, a main shaft, digit wheels rotatably mounted on said shaft, radially movable type bars mounted 10 in said digit wheels, cam discs cooperating with the said type bars, means securing the said cam discs against rotation relatively to the said main shaft, and means for effecting relative rotation of said digit wheels. 15

2. In a machine of the character described, a main shaft, digit wheels rotatably mounted on said shaft, radially movable type bars mounted in said digit wheels and provided with laterally projecting pins, cam discs secured against rotation relatively to the main shaft and having cam slots cooperating with the said pins, and means for effecting relative rotation of said digit wheels. 20

3. In a value printing machine of the type described, a shaft, digit wheels rotatably mounted on said shaft, radially adjustable type bars carried by said digit wheels, cam discs secured against rotation relatively to the main shaft and coacting with the type bars to cause displacement of the latter, and means for relatively rotating the several digit wheels. 25 30

4. In a value printing machine of the type described, a shaft, digit wheels rotatably mounted on said shaft, radially adjustable type bars carried by said digit wheels, cam discs cooperating 35 with the said type bars and having lugs thereon rigidly mounted on the main shaft, a bar rigidly connected with the said discs and bearing against said lugs whereby the discs are secured against rotation relatively to the main shaft, and means 40 for relatively rotating the several digit wheels. 40
